UNITED STATES PATENT OFFICE.

CHARLES JOHN NOKE, OF STOKE-UPON-TRENT, ENGLAND, ASSIGNOR TO WILLIAM S. PITCAIRN, OF EAST ORANGE, NEW JERSEY.

DESIGN FOR A PLATE.

43,555.

Specification for Design.

Patented Feb. 11, 1913.

Application filed November 8, 1912. Serial No. 730,268. Term of patent 7 years.

To all whom it may concern:

Be it known that I, CHARLES JOHN NOKE, a subject of the King of England, residing at Stoke-upon-Trent, in the county of Stafford, England, have invented a new, original, and ornamental Design for Plates, of which the following is a specification, reference being had to the accompanying drawing, forming a part thereof.

The figure is a plan view of a plate illustrating my design.

I claim—

The ornamental design for a plate as shown.

CHARLES JOHN NOKE.

Witnesses:

PATTIE PLANT,
JOHN H. COPESTAKE.
